US00D949862S

(12) **United States Design Patent** (10) Patent No.: **US D949,862 S**
(45) Date of Patent: **** Apr. 26, 2022**

(54) **TERMINAL BLOCK ADAPTER FOR
PROCESS CONTROL DEVICE**

(71) Applicant: **MITSUBISHI POWER, LTD.**,
Kanagawa-ken (JP)

(72) Inventors: **Yuichi Yakushiji**, Yokohama (JP); **Koji Ikeda**, Yokohama (JP); **Tadayuki Mizoguchi**, Yokohama (JP); **Toshiaki Matsuoka**, Yokohama (JP); **Yoshikane Yamanaka**, Yokohama (JP); **Kenji Umino**, Yokohama (JP); **Takashi Shigemitsu**, Yokohama (JP); **Yoshinari Shirasaka**, Yokohama (JP); **Shinichi Yamawaki**, Yokohama (JP); **Hitoshi Matsumura**, Yokohama (JP); **Kazuya Kanno**, Yokohama (JP); **Yusuke Oobu**, Yokohama (JP)

(73) Assignee: **MITSUBISHI POWER, LTD.**,
Kanagawa-ken (JP)

(**) Term: **15 Years**

(21) Appl. No.: **29/748,172**

(22) Filed: **Aug. 27, 2020**

(51) LOC (13) Cl. **14-02**

(57) **CLAIM**

The ornamental design for a terminal block adapter for process control device, as shown and described.

DESCRIPTION

FIG. 1 is a front, top and left side perspective view of a terminal block adapter for process control device showing our new design;

FIG. 2 is a front, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines illustrate portions of the terminal block adapter for process control device that form no part of the claimed design.

1 Claim, 8 Drawing Sheets
